UNITED STATES PATENT OFFICE.

JOHN R. DAVENPORT, OF HOXIE, ARKANSAS.

TIMBER-CUTTING MACHINE.

1,338,977.

Specification of Letters Patent.

Patented May 4, 1920.

Application filed April 4, 1919. Serial No. 287,610.

To all whom it may concern:

Be it known that I, JOHN R. DAVENPORT, a citizen of the United States, residing at Hoxie, in the county of Lawrence and State 5 of Arkansas, have invented certain new and useful Improvements in Timber-Cutting Machines, of which the following is a specification.

My invention relates to new and useful 10 improvements in timber cutting machines and more particularly to that type embodying a "two man drag saw", whereby the machine facilitates the saw being used by one man instead of two.

15 An important object of my invention is to provide a device embodying spring means for redrawing a saw through timber after it has been drawn through the timber by manual means.

20 Another object of my invention resides in the provision of a device of the above mentioned character embodying a plurality of guide rollers, one of which may be adjusted, so as to facilitate proper placement 25 and operation of the saw.

Another object of my invention resides in the provision of a device of the above mentioned character embodying a supporting stake which is vertically adjustable so that 30 the machine may be placed in connection with logs of various diameters and thicknesses.

A still further object of my invention resides in the provision of a device as above 35 mentioned embodying supporting means which may be folded into close engagement with the body of the device to facilitate easy shipment of the invention.

A still further object of the invention resides in the provision of a device of the 40 above mentioned character having means on one end thereof for penetrating timber to support one end of the device.

Still another object of the invention resides in the provision of a device including 45 a plurality of cables, one of which is wound upon a drum while the other two cables are wound upon the axle of the drum, the first mentioned cable being connected with the 50 saw while the last two named cables are connected with coiled springs for actuating the drum.

Other objects and advantages of my invention will become apparent during the 55 course of the following description.

In the accompanying drawings forming a part of the description and wherein like numerals are employed to designate like parts throughout the several views,

Figure 1 is a side elevation of the invention as applied to a log.

Fig. 2 is a top plan of the same.

Fig. 3 is a transverse vertical section taken on the lines 3—3 of Fig. 2.

Fig. 4 is a longitudinal vertical section 65 through the invention.

Fig. 5 is a bottom plan.

Fig. 6 is an end elevation of the invention, and

Fig. 7 is a vertical transverse section 70 through the invention adjacent the drum, parts of the drum being broken away to disclose its construction.

In the drawings, wherein is shown a preferred embodiment of my invention, the numeral 8 designates the body portion of the invention, and consists of an elongated beam. Adjacent one end of this beam I provide a pair of spaced vertical standards 9, which form bearings for an axle 10 of the drum 11. 80 As more clearly shown in Fig. 7, the axle and drum are formed integral with each other.

The body portion 8 is provided with a pair of spaced slots 12, and these slots are 85 arranged adjacent the drum 11. As more clearly shown in Figs. 4 and 5 of the drawings, a grooved horizontal roller 13 is rotatably mounted in each slot. A pair of longitudinally extending spaced coil springs 14 90 are secured by one of their ends to hooks 15 secured to the underside of the body portion 8, substantially intermediate its ends. To the opposite ends of these coiled springs, I secure cables 16 which extend along the 95 underside of the body portion to engage the relative bottom of the grooved rollers 13, then through the slot 12 to be wound over the axle sections 10 and are secured thereto.

The saw cable 17 is secured to the groove 100 in the drum 11 and this cable is fed from the relative bottom of the drum, so that when the cable 17 is unwound from the drum, the cables 16 will be wound upon the axle sections 10 and thereby increase the 105 tension of the coiled springs 14. The cable 17 extends longitudinally of the body portion between a pair of grooved guide rollers 18 which are rotatably mounted upon the 110 upper face of the body portion adjacent the

slots 12, and are arranged vertically of the body portion. The free end of the cable 17 is provided with a hook 19 which is for detachable connection with the usual drag saw indicated by the numeral 20.

In the end of the body portion opposite the end thereof carrying the drum 11, I provide a plurality of openings 21, which are arranged transversely of the body portion. These openings are for the reception of the pin 22 upon which is rotatably mounted the vertical grooved guide roller 23. In Fig. 2 of the drawings, the guide roller 23 is shown in an adjusted position adjacent one side of the body portion 8 so that the cable 17 may engage with this roller and so that the drag saw 20 may be so positioned when cutting timber that one face of the saw engages the side of the body portion during the reciprocatory movement of the saw.

The transverse end of the body portion adjacent the guide roller 23 is provided with a plurality of longitudinally extending prongs or spurs 24 which are jabbed into the timber when it is desired to position the machine in operative relation with the timber.

To the under side of the opposite end of the body portion, I hinge a member 25 by means of the hinges 26. This member is provided with a bolt 27, as more clearly shown in Fig. 4 of the drawings and this bolt is of such length that its free threaded end extends a substantial distance beyond the outer face of this member. A relatively large washer 28 and a nut 29 is received upon the threaded end of the bolt for a purpose to hereinafter appear.

In order to support the body portion of the machine in a horizontal plane with relation to the timber I provide a supporting stake 30 which is more clearly shown in Fig. 6 of the drawings. I provide a longitudinally extending slot 31 in this supporting stake and this slot extends from the upper end of the stake to a point adjacent the opposite pointed end of the stake 32. The bolt 27 extends through the slot 31 and in order that the supporting stake may be held in close engagement with the member 25 and in adjusted positions therewith, the nut 29 is rotated to force the washer into close engagement with the outer face of the stake upon opposite sides of the slot 31. In order to close the upper open end of the slot 31, I provide a bolt 33 which passes transversely through the free end of the supporting stake to bridge the slot.

In order that the stake may be held securely in the ground and in a vertical position, I provide a pair of supporting legs 34 which are pivotally connected to the stake by means of the bolts or other suitable means 35. A plurality of pairs of openings 36 are provided in the supporting stake so

that the legs 34 may be adjusted vertically in relation to the stake.

When it is desired to employ the invention and the stake 30 and legs 34 are folded in close engagement with the under side of the body portion, the device is taken as a whole and jabbed into the log, so that the prongs or spurs 24 penetrate the log and are held firmly therein. The legs 34 and stake 30 are then swung downwardly, and as the stake 30 is adjusted by means of the bolt 27 with relation to the body portion, the stakes and legs are driven into the ground, until the body portion obtains a horizontal position. If the pointed ends of the legs and stakes engage an obstruction in the ground and it is impossible to drive them down farther, the nut 29 may be loosened upon the bolt 27 so as to permit the washer 28 to loosely engage the stake so that the body portion 8 together with the bolt 27 may be adjusted in the slot 31 until the body portion is correctly positioned. The nut 29 is then of course tightened sufficiently to cause the washer 28 to bind against the outer face of the stake upon opposite sides of the slot 31.

When the machine is in position, the drag saw is then connected with the hook 19 carried by the cable 17. The operator stands upon the opposite side of the log from that on which the machine is arranged, grasps the end of the drag saw and pulls the same toward him. This of course makes the initial cut in the timber and causes the cable 17 to feed from the under side of the drum 11. The rotation of the drum of course causes its integral axle section 10 to rotate, which action winds the cable 16 upon these axle sections against the tension of the coiled springs 14. After the operator has drawn the drag saw toward him as far as is desired, he releases his pull and the reaction of the coiled springs 14 will cause the drum 11 to rotate in such a manner that it will rewind the cable 17 thereon and accordingly draw the drag saw toward the drum 11. As more clearly shown in Fig. 2 of the drawings, one face of the saw may engage with one side of the body portion to properly guide the saw, when the guide roller 23 is adjusted to the opening 21 which is nearest this side of the body portion. When the saw is positioned as shown in Fig. 2, it will be seen that the cable 17 engages one of the vertical guide rollers 18 so that the cable will not be caused to slide off of either side of the drum 11.

The foregoing description and the drawings have reference to what may be considered the preferred or approved form of my invention. It is to be understood that I may make such changes in construction and arrangement in combination of parts, materials, dimensions, etc., as may prove expedient to fall within the scope of the appended claims.

Having thus fully described my invention what I claim as new and desire to secure by Letters Patent, is:

1. A timber cutting machine comprising a body portion, a saw, an axle mounted upon said body portion, a drum mounted upon said axle, a cable connected to said drum and said saw, springs secured to said body portion and a pair of cables connected to said springs and wound over said axle, whereby said cables are wound upon the axle when the first named cable is unwound from the drum.
2. A timber cutting machine comprising a body portion, a saw, an axle mounted upon said body portion, a drum mounted upon said axle, a cable connected to said drum and said saw, said body portion having a pair of slots therein, a roller mounted in each slot, a pair of coiled springs secured to said body portion, and cables connected to said springs and to said axle and extending through said slot to engage said rollers

whereby the drum is rotated to rewind the cable thereupon after the cable has been unwound against the tension of said springs. 25

3. A timber cutting machine comprising a body part, a saw, means for drawing the saw in one direction, means on one end of said body part for supporting engagement with timber, a member hingedly connected 30 with the opposite end of the body part, a stake adjustably associated with said member and adapted to engage the end of the body part to which said member is hinged, and means carried by said member and co-operating with said stake to retain the same in various adjusted positions with relation to the body part.

In testimony whereof I affix my signature in presence of two witnesses.

JOHN R. DAVENPORT.
